UNITED STATES PATENT OFFICE

118,117

DESIGN FOR A MERCANDISE DISPLAY
RACK

Melvin C. Houle, Chicago, Ill.

Application August 28, 1939, Serial No. 86,914

Term of patent 7 years

To all whom it may concern:

Be it known that I, Melvin C. Houle, a citizen of the United States, residing at Chicago, in the county of Cook and State of Illinois, have invented a new, original, and ornamental Design for a Merchandise Display Rack, of which the following is a specification, reference being had to the accompanying drawing, forming part thereof.

The elliptical portion shown in Figures 1 and 3 represents a cut-out in the front portion of the hood for receiving a glass panel or other panel for advertising purposes.

I claim:

The ornamental design for a merchandise display rack, substantially as shown and described.

MELVIN C. HOULE.

CERTIFICATE OF CORRECTION.

I sign No. 118,117.

December 19, 1939.

MELVIN C. HOULE.

It is hereby certified that the above numbered design patent was erroneously issued to the inventor, said "HOULE", whereas said patent should have been issued to Owen Housholder and David C. Cohen, of Chicago, Illinois, copartners, doing business as Crystal Manufacturing Co., as assignees of the entire interest therein, as shown by the record of assignments in this office; and that the said Letters Patent should be read with this correction therein that the same may conform to the record of the case in the Patent Office.

Signed and sealed this 20th day of February, A. D. 1940.

(Seal)

Henry Van Arsdale,
Acting Commissioner of Patents.
